FIG. 2

FIG. 1

Inventor

B. E. Persinger

By *Watson E. Coleman*
Attorney

UNITED STATES PATENT OFFICE

BERNARD E. PERSINGER, OF WASHBURN, NORTH DAKOTA

BARREL LIFTER

Application filed April 16, 1929. Serial No. 355,567.

This invention relates to the class of supports and pertains particularly to a structure designed for the support of receptacles such as barrels and the like.

5 The primary object of the present invention is to provide a barrel support which will carry the barrel in such a manner that the same may be easily tipped for emptying or for the purpose of making the contents thereof 10 flow to one end equipped with a draw-off faucet.

Another object of the invention is to provide a barrel support having means in the form of a platform for carrying the barrel 15 and means whereby the platform and barrel carried thereby may be raised to a desired elevation.

A further object of the invention is to provide a barrel handling device having a platform wherein means is provided for facilitating the positioning of the barrel upon the platform.

The invention will be best understood from a consideration of the following detailed description taken in connection with the accompanying drawings forming a part of the present invention with the understanding, however, that the invention is not confined to any strict conformity with the showing of the drawing but may be changed or modified so long as such changes or modifications mark no material departure from the salient features of the invention as expressed in the appended claims.

35 In the drawings:—

Figure 1 is a view in side elevation of the lifting device embodying the present invention.

Figure 2 is a sectional view taken upon the line 2—2 of Figure 1.

Figure 3 is a transverse sectional view taken upon the line 3—3 of Figure 2.

Figure 4 is a detailed view of the lifting mechanism a part thereof being in section.

40 Figure 5 is a sectional view taken upon the line 5—5 of Figure 1.

Referring to the drawings in detail it will be seen that the barrel supporting apparatus embodying the present invention has a main frame structure 1 which comprises a pair of

spaced substantially parallel uprights 2 connected across their top ends by the horizontal bar 3 and mounted at their lower ends each upon the central portion of one of a pair of spaced parallel base bars 4 and at their lower ends these uprights are braced by the inclined side members 5 which extend between the uprights and the supporting base bars in the manner shown.

Secured to the inner face of each side member 2 of the structure, substantially midway between the ends thereof, is a lifting device which is indicated as a whole by the numeral 6. Each of these lifting devices comprises a casing 7 through which runs a vertical rack bar 8, the lower end of the bar 8 carrying a cap 9 from which extends a pair of guide arms 10 between which the adjacent frame member 2 is slidably positioned.

At its inner side the cap 9 of each rack 70 bar carries an inwardly projecting stirrup 11 which receives a trunnion carried by a barrel supporting frame as hereinafter described.

Each casing 7 is open at one side and there projects from this open side a lever 12 the inner end of which is of substantially U shaped cross sectional design and has the side walls thereof traversed by the pin 13 which extends between and connects the side walls of the casing in the manner shown. Between the side walls of the lever 12, the pin 13 carries a relatively long pawl 14, the lower end of which is normally forced inwardly against the toothed face of the adjacent rack bar 8 in the manner shown, under the urge of a suitable spring 15.

At its inner end the lever carries a second pawl as indicated at 16, this pawl being mounted upon a pin 17 which connects and is carried by the side walls of the lever 12 forwardly of the pawl 14. Like the pawl 14, the pawl 16 is normally urged inwardly by a spring 18 for engagement with the teeth of the adjacent rack.

Mounted upon the pin 13 of each lifting device is a small plate 12a which carries a handle 13a and has depending therefrom a leg 14a. The edge of the plate opposite the leg 14a is formed to provide a pair of spurs which are indicated by the numerals 14b 100

and 14c, there being a recess formed therebetween, as shown. Each of the pawls 14 and 16 carries a pin 15a each of which lies adjacent one of the spurs of the plate 12a, as shown. This plate and the spurs are provided to facilitate the reverse operation of the lifting device to permit the smooth lowering of the structure supported thereby.

Supported directly beneath each plate 12a upon a suitable bracket 16a is a coiled spring 17a which is connected with the adjacent free end of the leg 14a and normally presses upwardly thereagainst.

In the operation of the lifting device for raising the barrel supporting structure the lever 13a is raised. When the structure is to be lowered the lever 13a of each lifting device is pressed down to the point where the spurs 14b and 14c will be brought to position under the pins 15a of the pawls. The spring 17a will assist in holding the plate 12a in this position. By then raising the lever 12 of the lifting device the short pawl 16 is released from the rack bar through contact of the pin 15 carried thereby with the underlying spur 14c, the top face of which is sloped so that the pawl will be moved outwardly away from the leg, the long pawl holding the rack bar against downward movement. By then lowering the lifting lever 12, the short pawl will be raised a notch higher up on the rack and will be released against it so that it will lift the rack slightly and allow the long pawl to be released. By then again raising the lifting lever the rack will be lowered and this operation can be repeated until the barrel carrying frame is lowered the desired distance.

Positioned within the frame 1 is a platform 19 which is here shown as being of open construction, the same being preferably of angle iron. As shown, this platform 19 is substantially semicircular at one side and is square at the opposite side, the square side of the platform having mounted thereacross adjacent a rigid bar 20, a roller 21. As shown, the side of the platform opposite the roller and the sides directly connecting therewith are provided with the upstanding flange 22, which prevents a barrel from sliding from the platform when placed thereon, it, of course, being understood that the end of the barrel is started onto the end of the platform over the roller 21 and slid toward the round side thereof.

During this operation the platform is placed upon the cross bars 23 which connect the lower or base members 4 of the frame.

From the platform 19 there extends upwardly a pair of side bars 24 each of which carries, intermediate its ends and upon its outer face, a trunnion pin 25 which is designed to rest in a stirrup 11 carried by the adjacent toothed rack 8. The upright bars 24 of the barrel supporting platform are con-

nected at one side by a series of semicircular bands 26 and coacting with each of these bands 26 and positioned upon the opposite side of the uprights 24 are shiftable semicircular bands 27 each of which is hingedly connected at one end to an upright 24 as indicated at 28 and carries at its other end a latch arm 29 which is pivoted thereto. These shiftable bands form, in cooperation with the fixed bands 26, hoops designed to engage about a barrel to hold it in position upon the platform 19.

Each of the latch members 29 carries an elongated loop 30 which is designed to engage one of a plurality of hooks 31 carried upon the outer face of the adjacent end of a fixed band. From this it will be readily understood that when the loops 30 of the latches 29 are engaged over one of the hooks 31 and the latch 29 swung inwardly to position against the body of the band by which it is carried, the shiftable band will be drawn tightly about a barrel positioned therein.

From the foregoing description it will be apparent that after placing a barrel in upright position upon the platform 19 and securing the hoops or bands thereabout to hold it in place, the platform and barrel may be readily raised by manipulation of the levers 12 of the lifting elements 6 until an elevation is reached which will permit of the tilting or oscillation of the barrel and platform about the trunnion 25.

Having thus described my invention, what I claim is:

A barrel lifting and handling device comprising a base, an upright frame carried by the base and including a pair of spaced members, a barrel supporting platform pivotally arranged in the frame between the said members, a lifting element carried by each of said members upon its inner face and including a vertically reciprocable rack and means for actuating the same, a slide carried by each rack and engaging the adjacent members, a carrying stirrup carried by each slide, and supporting trunnions carried by the body supporting platform and designed to position in one of said stirrups said platform being adapted to engage one end of a barrel for normally holding the barrel in substantially upright position.

In testimony whereof I hereunto affix my signature.

BERNARD E. PERSINGER.
